UNITED STATES PATENT OFFICE.

FREDERICK C. RUNGE, JR., OF HOUGHTON, MICHIGAN.

SILK-FLOSS HOLDER.

SPECIFICATION forming part of Letters Patent No. 745,296, dated November 24, 1903.

Application filed February 24, 1903. Serial No. 144,700. (No model.)

To all whom it may concern:

Be it known that I, FREDERICK C. RUNGE, Jr., a citizen of the United States, residing at Houghton, county of Houghton, and State of Michigan, have invented new and useful Improvements in Silk-Floss Holders, of which the following is a specification.

My invention relates to improvements in silk-floss holders designed especially for use by dentists.

The object of my invention is to provide an inexpensive form of receptacle in which the floss may be stored and withdrawn as used, but one hand being required for the withdrawal and separation of the desired length of the filament or thread.

In the following description reference is had to the accompanying drawings, in which—

Figure 1 is a side view of my invention, partially broken away to show the spool-supporting pin. Fig. 2 is a front view of the same. Fig. 3 is a sectional view drawn transversely of the receptacle and spool-supporting pin, and Fig. 4 is a view of the invention as seen from the under side.

Like parts are identified by the same reference characters throughout the several views.

The side walls 1 and bottom 2 are formed integrally of a piece of sheet metal stamped into the desired shape and provided with ears 3, having suitable apertures for the reception of screws 4, by means of which the receptacle is secured to any suitable support 5, usually to the under surface of a supporting stand or tray, the support forming the top wall of the receptacle. The rear wall 6 is permanently secured to the side and bottom walls 1 and 2 and is provided with a pin 7, projecting centrally within the receptacle, the pin being secured to the rear wall in any suitable manner. The spool 8, which supports the floss, is adjusted upon the pin 7, as illustrated in Fig. 3.

At the front of the receptacle I provide a hinged lid or door 10, connected with one of the side walls 1 by the hinge 11. The door 10 is provided with an open-sided slot or aperture 12, through which the thread or filament of floss passes to the exterior.

13 is a knife secured to one of the walls 1 and projecting past the edge of the door 10

opposite the hinge 11. This knife is provided with a notch, in which a latch 14, carried by the door 10, is adapted to engage when the door is closed. The end of the floss thread 55 which projects through the aperture 12 is given one turn over the knob 15, connected with the door, the friction of the thread upon the knob furnishing sufficient resistance to the withdrawal of the floss to enable the operator to sever the thread by drawing it across the knife 13 with one hand. The knob is located at a sufficient distance from the knife so that a projecting portion of the thread end will always be left in a position where it 65 can be conveniently grasped by the operator. When the supply of floss is exhausted, it may be readily replenished by raising the latch 14, opening the door 10, and substituting a full spool for the one which is exhausted.

While I have described my invention with especial reference to its use for holding silk floss, it is obvious that it may be employed for holding any form of thread-carrying spool.

Having thus described my invention, what 75 I claim as new, and desire to secure by Letters Patent, is—

1. A receptacle having a fixed rear wall provided with an interior spool-supporting pin; a front wall, hinged to one side of the receptacle and provided with a delivery-aperture; a resisting device mounted on the front wall; and a thread-cutting blade mounted on one of the side walls.

2. A receptacle having a fixed rear wall provided with an interior spool-supporting pin; a front wall hinged to one side of the receptacle and provided with a delivery-aperture; a resisting device mounted on the front wall; and a thread-cutting blade mounted on one of the side walls, together with a latch connected with the front wall and adapted to engage in a notch in said blade.

3. A receptacle having side and bottom walls formed integrally of a single piece of metal 95 and provided with ears for attachment to a suitable support forming the top wall; a rear wall provided with an interiorly-projecting, spool-supporting pin; a front wall hinged to one of the side walls and provided with a slot; 100 a friction-knob located upon the front wall; a blade located on one of the side walls and

projecting past the edge of the front wall; and a latch pivotally connected with the front wall and adapted to engage in a notch in said blade.

4. The combination with a receptacle provided with an aperture in one of its walls; an interior spool-supporting pin; a thread-cutting blade located on said receptacle; and a friction-knob projecting from one of the walls of the receptacle, whereby a thread drawn

through said aperture may be wound upon the knob, and drawn frictionally therefrom across said blade.

In testimony whereof I affix my signature in the presence of two witnesses.

FREDERICK C. RUNGE, JR.
